E. RENAUD

RAZOR BLADE HOLDER

Filed Oct. 1, 1923

UNITED STATES PATENT OFFICE.

EUGENE RENAUD, OF MONTREAL, QUEBEC, CANADA.

RAZOR-BLADE HOLDER.

Application filed October 1, 1923. Serial No. 665,985.

To all whom it may concern:

Be it known that I, EUGENE RENAUD, a subject of the King of Great Britain, residing at Montreal, Province of Quebec, Canada, have invented certain new and useful Improvements in Razor-Blade Holders; and I do hereby declare that the following is a full, clear, and exact description of the invention, such as will enable others skilled in the art to which it appertains to make and use the same.

The present invention pertains to a novel device for holding safety razor blades for sharpening. Although the device hereinabove described is particularly adapted for this purpose, it will be obvious that it may be used for other purposes where it is desired to obtain a firm grasp on a blade, for example as in cutting.

The device comprises a pair of strips between which the blade is to be grasped. Each strip is formed with a pair of perforations from each of which is projected a tooth. The teeth of one strip are adapted to pass through the perforations of the remaining strip, and teeth are further constructed for mutual interlocking. By means of this arrangement a razor blade, which is also perforated to receive the teeth, is firmly held between the strips.

These perforations and teeth are formed at one end of the strips, hereinafter referred to as the forward end. At the remaining end of each strip is formed a device for normally holding the teeth in interlocking engagement.

The invention is fully disclosed in the following description and in the accompanying drawings in which:

Figure 1 is a perspective view of a device constructed in accordance with the invention;

Figure 2 is a partial longitudinal section thereof;

Figure 3 is a fragmentary perspective view of the grasping end;

Figure 4 is a plan view of one of the strips;

Figure 5 is an edge view thereof;

Figure 6 is a plan view of the remaining strip;

Figure 7 is an edge view thereof;

Figure 8 is an edge view of both strips previous to their locking engagement;

Figure 9 is an edge view of the strips in locked position;

Figure 10 is a perspective view of a modified form; and,

Figure 11 is a section on the line 11—11 of Figure 10.

Reference will now be had to these views by means of like characters which are employed to designate corresponding parts throughout.

The device comprises two strips 1 and 2 which will be described separately. The strip 1 is formed of steel or other suitable metal and has the gripping end thereof narrowed as at 3 for convenience. In this end are cut a pair of perforations 4, and from the rear edge of each of these perforations projects a tooth 5 which points towards the forward end of the strip.

These teeth and perforations may be formed by stamping in an obvious manner. The handle or rear end of the strip is formed with a tongue 6 the end of which is enlarged as at 7.

The complementary strip 2 is also reduced at its forward end as at 8. This end is also formed with a pair of perforations 9 which are adapted to align with the perforations 4 when the strips are placed in juxtaposition, as shown in Figures 1 and 9. Teeth 10 project from the forward edges of the perforations in the direction of the handle or rear end of the strip. The latter end is formed with an inclined portion 11 in which is cut an aperture 12.

When the razor blade is to be clamped into the device, it is placed over one of the strips so that the perforations of the blade receive the teeth. The remaining strip is superposed so that the teeth thereof pass through the perforations of the blade and into the perforations of the first mentioned strip, as illustrated in Figure 9. Since the teeth on the two strips point in opposite directions, the blade is firmly grasped between the strips. The tongue 6 is slipped into the aperture 12. Because of the inclined portion 11 the strip having the tongue slips forwardly as a result of which the teeth on the tongue strip are held

against the teeth of the remaining strip. When the strips are held in the hand by the handle, the teeth are maintained in interlocking engagement by the pressure of the hand. This follows from the fact that the rise slopes downwardly towards the forward ends of the strips, so that the tongue strip having the forwardly pointing teeth is prevented from slipping back.

10 In Figures 10 and 11 is illustrated a further modification designed for use when only one edge of the blade is to be sharpened. The strips are formed with perforations, teeth, tongue and an aperture in the 15 same manner as the embodiment already described. At the forward ends of the strips, one of the edges of each has a bead 13 formed partially along its length. When the two strips are interlocked, the beads engage one another forming a housing for the 20 blade edge which is not to be sharpened, the remaining edge being exposed as illustrated.

While a specific embodiment of the invention has been illustrated and described, 25 it is to be understood that various alterations in the details of construction may be made without departing from the spirit of the invention as indicated by the appended claims.

Having thus fully described the invention, what I claim as new and desire to protect by Letters Patent is:—

1. A razor blade holder comprising a pair of strips, each of said strips having a pair of perforations therein, teeth projecting from each of said perforations, the teeth on one of the strips pointing oppositely to the teeth of the remaining strip, one of said strips having a tongue at one end, an inclined portion formed at the corresponding end of the other strip, said portion having an aperture cut therethrough adapted to receive said tongue.

2. A razor blade holder comprising a pair of strips, each having a pair of perforations cut therethrough, teeth projecting from said perforations, the teeth of one of said strips being adapted for interlocking engagement with the teeth of the remaining strip, one of said strips having a tongue at one end, an inclined portion formed on the corresponding end of the other strip, said portion having an aperture cut therethrough adapted to receive said tongue.

In witness whereof I have hereunto set my hand.

EUGENE RENAUD.
